UNITED STATES PATENT OFFICE.

ALBERT SIDNEY BRADSHAW, OF SIMMONS, TEXAS

WELL-DRILLING MACHINE.

1,369,614.

Specification of Letters Patent. Patented Feb. 22, 1921.

Application filed August 21, 1920. Serial No. 405,069.

To all whom it may concern:

Be it known that I, ALBERT SIDNEY BRADSHAW, a citizen of Live Oak county, Texas, U. S. A., residing at Simmons, in the county 5 of Live Oak and State of Texas, have invented new and useful Improvements in Well-Drilling Machines, of which the following is a specification.

This invention relates to well drilling devices and has for its object the provision of an improved rig designed particularly for drilling oil wells and including novel drive mechanism for conveying power from an engine to a windlass structure for reeling 15 in the drilling cables.

An important object is the provision of a device of this character in which the windlass structure includes two reels upon one of which the main cable is wound and upon 20 the other of which the sand line is wound, clutch mechanism being provided whereby either of the reels may be driven to the exclusion of the other.

Another object is the provision of a device of this character provided with separate control levers, one of which is to operate the clutch mechanism and the other of which operates a brake for stopping the rotation 25 of the reel when the drill strikes the bottom 30 of the hole.

An additional object is the provision of a device of this character which will be comparatively simple and inexpensive in manufacture, highly efficient in use, easy to operate, durable in service, and a general improvement in the art.

With the above and other objects and advantages in view, the invention consists in the details of construction to be hereinafter 40 more fully described and claimed and illustrated in the accompanying drawings in which—

Figure 1 is a side elevation of my complete device,

Fig. 2 is an elevation of the opposite side, the upper portion of the derrick being omitted,

Fig. 3 is a rear elevation, that is looking at the end most remote from the derrick,

Fig. 4 is a front elevation, the derrick being omitted,

Fig. 5 is a plan view,

Fig. 6 is a longitudinal sectional view through the windlass structure,

Fig. 7 is a face view of one of the clutch members,

Fig. 8 is a detail edge view of the slidable clutch element, showing its mounting,

Fig. 9 is an elevation of the upper end of the derrick, showing the pulleys edgewise, 60 and

Fig. 10 is a detail section showing the brake mechanism.

Referring more particularly to the drawings, the numeral 10 designates a derrick 65 of ordinary construction and of any desired height having mounted at its top a pair of pulleys 11 and 12 from which are trained the main cable 13 carrying the drill, and the sand line 14. The numeral 15 designates 70 heavy timbers which are arranged in spaced parallel relation upon the top of the ground and two legs of the derrick are preferably secured to or rested upon these timbers so as to hold all parts of the device properly 75 associated.

Any suitable platform structure or cross beams 16 may be employed upon these timbers 15 whereby to form a strong support. At one side of the framework thus formed 80 are located benches 17 and 18, the former being higher than the latter and serving as a seat for the operator and the latter for a purpose to be hereinafter described.

Mounted upon the frame formed by the 85 timbers 15 and beams 16 at the end most remote from the derrick 10, is an engine 19 of any ordinary or preferred type which has its shaft 20 provided at one end with a friction disk 21. The various control features 90 of the engine are not described as they are conventional. Journaled transversely of the timbers 15 is a counter-shaft 22 mounted in suitable bearings 23 and carrying adjacent one end a pinion 24 and carrying at 95 its other end a relatively large wheel 25.

In order to drive the counter shaft from the engine, I provide a bar 26 pivoted, as at 27, and carrying an arm 28 upon which is journaled a friction disk 29 adapted to engage between the wheel 25 and disk 21. A suitable retaining catch 30 is provided for holding the bar 26 down with the disk 29 carried thereby in operative engagement with the disk 21 and wheel 25. In case it 105 is desired to let the engine run idle, it is merely necessary to disengage the catch 30 and move the bar 26 upwardly.

Mounted on the supporting frame nearest the derrick is a windlass structure which includes a hollow supporting shaft 31 upon which are mounted spools or reels 32 and 33,

about the former of which is wound the main cable 13 and about the latter of which is wound the sand line 14. It will be observed that the main reel 32 is cut away so as to provide more space for the relatively large main cable. These reels are revolvable upon the shaft 31. Secured upon one end of the shaft 31 is a gear 34 which meshes with the pinion 24 of the counter shaft. 5

10 Slidable longitudinally through the hollow shaft 31 is a clutch shaft 35 which carries at one end a grooved collar 36 engaged by a fork 37 carried by a lever 38 which is supported upon the bench 18. Slidable upon 15 but non-rotatable upon the hollow shaft 31 is a clutch member 39 formed as a disk provided on opposite sides with pins 40. Extending through this clutch member is a pin 41 which passes through elongated slots 20 42 in opposite sides of the hollow shaft 31 and which passes through a hole in the clutch shaft 35 so that this clutch member may be shifted longitudinally upon the shaft 31 by movement of the shaft 35. The 25 confronting ends of the reels 32 and 33 are recessed, as shown at 43 and 44, respectively, for the accommodation of the clutch member 39 and at the bottoms of the recesses the reels are provided with holes 45 for the reception of the pins 40 whereby either reel 30 may be locked for rotation with the shaft 31.

In order to prevent shifting of the clutch member too far, I provide the bench 18 with holes 46 within either of which may be engaged a stop pin 47 engageable by the lever 38. When it is desired to use the main reel 32 the pin 47 is disposed in such position as to be engaged by one side of the lever 38 and when it is desired to use the reel 33 the 40 pin 47 is so disposed as to be engaged by the other side of the lever.

Disposed in position to engage the adjacent rims of the reels 32 and 33, is a brake band 48 with which is connected a pivoted 45 lever 49 disposed within convenient reach of the operator. The purpose of this brake band is to stop rotation of the reels when the drill has reached the bottom of the hole so as to prevent back lashing of the cable.

50 In the operation of the device it will be seen that when the lever 38 is shifted to bring the clutch member 39 into such position that the pins 40 at one side thereof will engage within the holes 45 in the adjacent 55 end of the reel 32, assuming that the engine 19 is in operation and that the disk 29 is in engagement with the disk 21 and wheel 25, the reel 32 will be rotated and will wind up the cable 13 to elevate the drill. When the 60 drill is elevated the operator then shifts the lever 38 to neutral position whereupon the drill will be allowed to drop, unwinding the cable from the reel 32. When the drill strikes the bottom of the hole being drilled 65 the operator pulls upon the lever 49 and en-

gages the band 48 with the drums to prevent further rotation and subsequent back lashing of the cable. When it is desired to use the sand line the same operation is gone through with except that the lever 38 is moved to engage the clutch member 39 with the reel 33. 70

Pivoted upon the frame are latch members 50 and 51 adapted to enter holes in the flanges of the drums 32, and 33, respectively, whereby to lock either drum against movement when the other is being used. 75

From the foregoing description and a study of the drawings it will be apparent that I have thus provided a simply constructed and easily operated and controlled well drilling rig which will be highly efficient and which is free from complexity in every respect. 80

While I have shown and described the preferred embodiment of my invention, it is of course to be understood that I reserve the right to make such changes in the form, construction, and arrangement of parts as will not depart from the spirit of the invention or the scope of the subjoined claims. 90

Having thus described my invention, I claim:

1. A well drilling rig comprising in combination, a supporting frame, a derrick, an engine mounted upon the frame, a counter shaft journaled upon the frame, means for driving said counter shaft from the engine, a windlass structure driven from the counter shaft and including separate reels, one for the main drilling cable and the other for the sand line, a brake mechanism associated with said reels, and means for throwing either of said reels into operation comprising a hollow driven shaft operatively connected with the counter shaft, the reels being rotatable upon said hollow shaft, a clutch shaft slidable through said hollow shaft and carrying a clutch member, a lever connected with said clutch shaft, and said reels being each provided with a clutch face engageable selectively by said clutch member, and means for locking either reel against movement. 100

2. A well drilling rig comprising in combination a supporting frame, a derrick, an engine mounted upon the frame, a counter shaft journaled upon the frame, means for driving said counter shaft from the engine, a windlass structure driven from the counter shaft and including separate reels, one for the main drilling cable and the other for the sand line, a brake mechanism associated with said reels, and means for throwing either of said reels into operation comprising a hollow shaft upon which said reels are rotatably mounted, said shaft being provided with a longitudinal slot, a clutch shaft slidably disposed within said hollow shaft, means for shifting said clutch shaft, a clutch 115

member slidable upon said hollow shaft and having a transverse pin disposed through said slot and through said clutch shaft, and the meeting ends of said reels being formed 5 with clutch faces engageable by said clutch member.

3. A well drilling rig comprising in combination a supporting frame, a derrick, an engine mounted upon the frame, a counter 10 shaft journaled upon the frame, means for driving said counter shaft from the engine, a windlass structure driven from the counter shaft and including separate reels, one for the main drilling cable and the other 15 for the sand line, a brake mechanism associated with said reels, and means for throwing either of said reels into operation comprising a hollow shaft upon which said reels

are rotatably mounted, said shaft being provided with a longitudinal slot, a clutch shaft 20 slidably disposed within said hollow shaft, means for shifting said clutch shaft, a clutch member slidable upon said hollow shaft and having a transverse pin disposed through said slot and through said clutch shaft, and the meeting ends of said reels being formed 25 with clutch faces engageable by said clutch member, said meeting ends of the reels being recessed for the accommodation of the clutch member whereby to form a projection 30 therefor and the bottoms of the recesses being formed with holes engageable by pins on the clutch member.

In testimony whereof I affix my signature.

ALBERT SIDNEY BRADSHAW.
